Patented Oct. 27, 1908.

UNITED STATES PATENT OFFICE.

STEPHEN A. HOLMAN, OF GUADALOUPE, CALIFORNIA.

WRENCH.

No. 902,079.

Specification of Letters Patent.

Patented Oct. 27, 1908.

Application filed February 6, 1908. Serial No. 414,570.

To all whom it may concern:

Be it known that I, STEPHEN A. HOLMAN, a citizen of the United States, residing at Guadalupe, in the county of Santa Barbara and State of California, have invented certain new and useful Improvements in Wrenches, of which the following is a specification.

This invention has for its object a simple, durable and efficient construction of wrench that may be used on pipes, nuts, or other work, and which may be easily adjusted and reversed in operation to turn the work in one direction or the other without disengaging the tool therefrom.

With these and other objects in view as will more fully appear as the description proceeds, the invention consists in certain constructions, arrangements and combinations of the parts that shall be hereinafter fully described and claimed.

For a full understanding of the invention, reference is to be had to the following description and accompanying drawings, in which:

Figure 1 is a perspective view of my improved wrench, the handle portion being partly broken away; Fig. 2 is a longitudinal sectional view thereof; Fig. 3 is a detail perspective view of one of the head plates; Fig. 4 is a similar view illustrating a modification; and, Fig. 5 is a detail view illustrating the spring tension means between the handle portion and the jaw closing device.

Corresponding and like parts are referred to in the following description and indicated in all the views of the drawings by the same reference characters.

Referring to the drawing, the numeral 1 designates the jaws of my improved wrench which are shown in the present instance as particularly designed for pipe or rod work, although it is manifest that they may be designed as well for work on nuts and the like, each of said jaws being formed on its inner edge with a row of work engaging teeth 2. Each jaw 1 is also formed with an oblique slot 3. These slots receive pins or studs 4 that are secured in and which connect together the ends of spaced plates 5, which, together constitute the head of the tool. 6 designates the handle of the wrench, said handle being of any desired size and shape, and being composed of a bar in the present instance, as clearly illustrated in the draw-

ing. This handle is rigidly secured at one end between the ends of the plates 5 of the head by screws, rivets, or similar fastening devices.

A jaw adjusting and closing device 7, which in the present instance is in the form of a plate with a curved front edge is mounted between the jaws 1 and is mounted to move longitudinally between the plates 5 of the head, so as to project more or less from the forward end of the head or be retracted therein. For this purpose the jaw closing device or plate 7 is formed with a longitudinal slot 8 which accommodates a pin or stud 8^a extending through and secured in the two plates 5 between the studs or pins 4, as shown. At its rear end, the adjusting device 7 carries a pivot stud or pin 9 which extends therethrough and also through apertures formed in the rear ends of the jaws 1. This pivot pin 9 is of a length to also extend at both ends through longitudinally arranged slots 10 formed in the respective plates 5, washers being preferably mounted on the ends of the pivot stud and overlapping the head plates 5 as shown, the said pivot pin being secured in place by lock nuts or any desired fastening devices. As best seen in Fig. 1, each of the head plates 5 is formed with diverging recesses 11 that are preferably oblique as shown and that open inwardly on both sides of the slots 10. The rear end of the jaw closing device 7 is formed with a nipple or protuberance 12. The forward end of the handle 6 is formed with a corresponding nipple 13 and a coil expansion spring 14 has its ends slipped over the respective nipples 12 and 13 and exerts an outward pressure on the jaw closing device 7.

In order to maintain the pivot pin 9 within the main portion of the slots 10 and to prevent it from being entered into any of the laterally extending recesses 11, except when it is intended that it shall so enter, I provide either or both of the plates 5 with a guiding device 15, which, in the present instance is in the form of a longitudinally extending loop. This loop is laterally yieldable. If desired, the loop itself may be formed of spring metal or material rigidly secured at one end only to the plate 5 so as to obtain the yielding action, or, as illustrated in Fig. 4, the loop there designated 15^a may be hinged at one end as indicated at 16 and be yieldingly connected at its

other end to some portion of the head of the tool (as one of the screws or fastening devices that secure the head to the handle) by means of a spring 17.

5 In the normal unrestrained or inoperative relative positions of the parts, it is obvious that the expansion spring 14 will press the plate 7 forwardly out of the head of the tool and such movement of the plate will 10 effect the opening movement of the jaws. In the practical operation of the device, the jaws in this open position are applied to the work, and the forward end of the plate 7 is pressed against the work, as for instance, a 15 pipe, by the attendant pushing forwardly upon the handle 16. The spring 14 will now yield, and the plate 7 will be forced rearwardly in a longitudinal direction within the head and as a consequence will draw 20 the two jaws 1 towards each other and cause them to engage the work, this inward movement of the jaws being manifestly effected by the provision of the oblique slots 3, the relatively stationary pins 4 in the head and 25 the pivotal connection between the rear ends of the jaws, and the plate 7. After the jaws have thus been caused to engage the work, they may be forced to effectively grip the same and rotate it in the desired direction 30 by the operator pressing the handles 6 in any direction in which it is desired the work shall be turned. This lateral movement of the handle will cause the head to be rocked relative to the jaws and plates 7, and the 35 pivot pin 9 will be forced into one of the recesses 11, so as to increase the tension of the jaws upon the work and rotate the same as desired. It is clear that the guide device or loop 15 will yield to permit this rocking 40 action, and as soon as the lateral pressure upon the handle is released, it is obvious that the loop or guiding device 15 will react to again align the parts and bring the longitudinal slots 10 into registry with the pivot 45 pin 9, thereby permitting the jaws to release sufficiently for a fresh grip upon the work and a repetition of the operation. It is evident that, owing to the oblique depression of the recesses 11, this partial release of the 50 jaws will be effected even before the pivot stud 9 shall have reached the main slots 10, so that a fresh grip may be secured on the work to work the wrench as a tool of the ratchet type, without permitting the pivot 55 pin 9 to be disengaged entirely from the recess in which it has been lodged.

From the foregoing description in connection with the accompanying drawing, it will be seen that I have provided a very simple, 60 durable and efficient construction of adjustable reversible wrench, the parts of which may be cheaply manufactured and readily assembled and which will be durable, the jaw closing device or plate 7 practically effecting the automatic closing of the jaws

upon the pressure of the tool against the work preparatory to turning the wrench, and the guiding device that is in the present instance constituted by the loop 15 holding the head properly in line with the jaws and 70 jaw closing device, until it is desired to have such stud enter one of the lateral and oblique recesses 11 to tightly grip the wrench on the work. Manifestly by providing a plurality of these lateral branch slots or recesses 75 11 at different points along the head of the tool, longitudinally considered, the jaws may be adjusted properly and with precision to work of different diameters, before the head is tilted by the handle in one direction or the other to tightly bind the jaws upon the work and to turn the same.

Having thus described the invention, what is claimed as new is:

1. A wrench of the character described, 85 comprising a head, a handle connected to said head, jaws pivotally and slidably connected to said head, a jaw closing device adapted to engage the work between the jaws and having a longitudinally movable connection with the head, and a connection 90 between said jaw closing device and jaws and arranged to close the latter upon the rearward movement of the former relative to the head.

2. A wrench of the character described, comprising a head, a handle secured to the head, jaws formed with oblique slots, the head being provided with pins mounted in said slots, a jaw closing device mounted between said jaws and adapted to contact with the work, and having a longitudinally movable connection with the head, and a connection 100 between said jaw closing device and jaws arranged to swing the latter towards 105 each other upon the movement of the former rearwardly relative to the head.

3. A wrench of the character described, comprising a head, a handle secured to the head, jaws pivotally connected to the head, 110 a jaw closing device adapted to contact with the work and having a longitudinally movable connection with the head, a connection between said jaw closing device and the jaws arranged to close the former upon the rearward movement of the latter relative to the head, and a spring arranged to press the 115 jaw closing device forwardly.

4. A wrench of the character described, comprising a head, a handle connected to 120 said head, jaws pivotally connected to the head, a jaw closing device adapted to engage the work and having a longitudinally movable connection with the head, the rear end of said device being provided with a nipple, 125 the handle being provided with a coacting nipple, and a coil spring connected to said nipples and acting expansively on the jaw closing device.

5. A wrench of the character described, 130

comprising a head, a handle connected to said head, jaws having a pivoted and sliding connection with the head, a jaw closing device adapted to contact with the work and 5 having a longitudinally movable connection with the head, and also connected with the jaws, the jaw closing device being arranged to draw said jaws rearwardly and their outer ends towards each other upon the rear- 10 ward movement of the jaw closing device relative to the head, and means for permitting a limited simultaneous rearward and lateral movement of the jaws and jaw closing device relative to the head.

15 6. A wrench of the character described, comprising a head, a handle connected to said head, jaws having a sliding and pivotal connection with the head, a jaw closing device adapted to contact with the work and 20 having a longitudinally movable connection with the head, and a pivot pin connecting the rear ends of the jaws with the jaw closing device, the head being formed with a 25 longitudinal slot receiving said pin, as and for the purpose set forth.

7. A wrench of the character described, comprising a head, a handle connected to said head, jaws having a sliding and pivotal connection with the head, a jaw closing device adapted to contact with the work and 30 having a longitudinally movable connection with the head, and a pivot pin connecting the rear ends of the jaws with the jaw closing device, the head being formed with a 35 longitudinal slot receiving said pin, and with a laterally extending recess communicating with said slot.

8. A wrench of the character described, comprising a head embodying spaced plates, 40 a handle connected to said head at one end thereof, jaws mounted between said plates at the opposite end thereof and having a pivotal sliding connection therewith, a jaw clos-

ing plate mounted between said jaws and between said plates and having a longitudinally slidable connection with the latter, and a pivot pin connecting the rear ends of said jaws with said plate, the plates being provided with longitudinal slots and a plurality of registering lateral recesses opening into 50 said slots, and arranged to accommodate said pin, as and for the purpose set forth. 45

9. A wrench of the character described, comprising a head, a handle connected to said head, jaws having pivotal connection 55 with the head, a jaw closing device adapted to contact with the work and having a longitudinally movable and laterally movable connection with the head, and arranged upon the relative movement in one direction with 60 respect to the head to effect a closing of the jaws, and a laterally yieldable guide device connected with said jaw closing device and adapted to return the same for a longitudinal movement only relative to the head. 65

10. A wrench of the character described, comprising a head, a handle connected to said head, jaws having a pivotal connection with the head, a jaw closing device adapted to contact with the work and having a longitudinal and laterally movable connection 70 with the head, a pivot pin connecting the rear ends of said jaws with the jaw closing device, the head being provided with a slot and lateral recesses opening into the said slot 75 and adapted to accommodate said pin, and a laterally yieldable guide loop secured to said head in longitudinal alinement with said slot and encircling the pivot pin, as and for the purpose set forth. 80

In testimony whereof I affix my signature in presence of two witnesses.
